EUGENE W. SAWYER, OF MILWAUKEE, WISCONSIN, ASSIGNOR OF ONE-HALF TO
EDWARD C. BAUMANN, OF MILWAUKEE, WISCONSIN.

GATE-HINGE.

978,063.

Specification of Letters Patent.

Patented Dec. 6, 1910.

Application filed April 16, 1910. Serial No. 555,943.

To all whom it may concern:

Be it known that I, EUGENE W. SAWYER, a citizen of the United States, and resident of Milwaukee, in the county of Milwaukee, 5 and State of Wisconsin, have invented certain new and useful Improvements in Gate-Hinges; and I do hereby declare that the following is a full, clear, and exact description thereof.

10 My invention consists in what is herein particularly set forth with reference to the accompanying drawings and pointed out in the claims of this specification, its object being to provide simple, economical and durable gate-hinges that may be readily applied.

Figure 1 of the drawings represents a partly sectional side elevation of a fragment of a gate and post connected by hinges 20 in accordance with my invention; Fig. 2, a plan view of a detail of the structure partly in horizontal section on the plane indicated by line 2—2 in Fig. 1; Fig. 3, a transverse section of the same indicated by line 3—3 in Fig. 1, and Fig. 4, a horizontal section of another detail of the structure looking upward, this view being indicated by line 4—4 in Fig. 1.

Referring by numerals to the drawings, 30 5 indicates a gate-post, 6 each of a series of horizontal gate slats at suitable intervals apart and 7 each of a pair of parallel vertical tie-bars between which the gate-slats are fastened adjacent to said post in which the 35 gate-hooks 8 are driven. The tie-bars may be of wood or metal, plain or flanged, but it is preferable, as herein shown, to employ right-angled metal strips of suitable thickness, the same being bolted or otherwise rigidly secured in connection with the gate-slats.

The leaf of each gate-hinge herein shown 40 is a casting having a flat portion 9 that abuts an edge of a gate-slat, and an eye-shank portion 10 that extends vertically beyond the flat portion aforesaid to abut the inner end of said gate-slat, this shank being preferably provided with a notched lug 11 adjacent to said inner end of the aforesaid 45 gate-slat. The leaf is also provided with a longitudinal stiffening-rib 12, and a pair of parallel ears 13 that are bolted or otherwise fastened to the sides of the gate-slat, these 50 ears being adjacent to the outer end of said leaf. The leaf is further provided with a

pair of outwardly channeled, inwardly flat, arms 14 that extend at right angles from said leaf adjacent to the eye-shank portion 10 of same in a direction opposite that of said ears that are also at right angles to 60 said leaf. The channels of the leaf-arms 14 have close fit upon the tie-bars 7 of the gate to which said arms are bolted or otherwise rigidly secured.

From the foregoing it will be understood 65 that the leaf of each hinge straddles the gate-slat to which it is attached, and may abut the inner end of said slat. It also straddles tie-bars of the gate to which it is fastened. Hence the unions of the hinge leaves 70 and said gate are very rigid and not liable to loosen under the various conditions to which they will be ordinarily subjected, while at the same time sagging of the aforesaid gate on the gate-hooks is prevented 75 because of the rigidity of said unions.

The gate-hook 8 of each hinge does not differ from those of ordinary construction, except that it is preferably provided with a forward flange 15 for engagement with 80 the notch in the lug 11 of the leaf when the gate is closed, this engagement serving to prevent a lift of said gate to separate the same from the post 5 in which the gate-hooks 85 are driven.

The hinge-leaves may be so disposed that each of them will have engagement of its notched lug 11 with a gate-hook flange 16 when the gate is closed, or they may be arranged as herein shown to have only one of 90 them effect such an engagement, and it is obvious that a solid block having channeled sides may be employed instead of the hinge-leaf arms herein shown and described, these arms being virtually the remainder of such 95 a block centrally recessed to lighten the same.

I claim:

1. A gate-hinge having the leaf thereof provided with vertically extending channel- 100 arms adjacent to the eye-shank of same for the engagement of vertical tie-bars of a gate to which they are attachable, said leaf being also attachable to a gate-slat against an edge of same.

2. A gate-hinge having the leaf thereof provided with vertically extending channel-arms adjacent to the eye-shank of same for the engagement of vertical tie-bars of a gate 110 to which they are attachable, and also pro-

vided with vertical ears that extend therefrom in a direction opposite that of the arms, said ears being attachable to a gate-slat facing the sides of same.

- 5 3. A gate-hinge having the eye-shank of its leaf vertically extended to abut an end of a gate-slat to which the leaf is secured against an edge of same, and channel-arms likewise extended in the opposite direction
10 from the extension aforesaid adjacent to said shank for the engagement of vertical

tie-bars of a gate to which they are attachable.

In testimony that I claim the foregoing I have hereunto set my hand at Milwaukee in ¹⁵ the county of Milwaukee and State of Wisconsin in the presence of two witnesses.

EUGENE W. SAWYER.
